UNITED STATES PATENT OFFICE

HELENE KOMUSIN, NÉE LIEDTKE, OF BERLIN, GERMANY

ROLLING STAMP WITH COUNTING MECHANISM FOR PRINTING PURPOSES OF ANY KIND

Application filed March 22, 1922, Serial No. 545,892, and in Germany December 20, 1920.

This invention relates to a machine for printing value stamps in which the printing roll is connected with counting mechanisms.

In counting and printing apparatus of known type rolls or disks are used as carriers for the several values, and these value carriers are designed each for a single value or each for several different values, the stamps printed being recorded by a counting mechanism merely as regards number without consideration of the value of the stamp which has been printed.

With the apparatus of known construction it is further not possible to divide a single value carrier into sections which are designed each for a stamp of different values so that every succeeding division of the roll or printing cylinder is designed for a stamp of twice the value as the preceding stamp or of a value which is increased at a determined ratio. None of the apparatus of known type comprises a device which permits to ascertain how much of a predetermined amount of value has been already spent or which amount is still at disposal.

This invention has for its object to arrange on a printing cylinder any number of stamps of different values. The values are doubled or increased in any other proportion by means of a reversing device and adjusted so that they are ready for use. The stamps which are being printed are at the same time registered not according to the number but to the value so that the total value of all the stamps which have been printed is printed on the paper together with each individual stamp, only one counting mechanism being required.

In conformity with the carriers of the value stamps the feeding devices for operating the counting mechanism can be also increased as regards value simultaneously with the value increase of the stamp carriers, a common shaft being used for these two adjusting operations.

This is effected with the aid of a novel feeding device which produces the changes according to the shape of the links of chains with feeding teeth alternating with the gear of feed wheels, the reversing of the value

degrees being prevented by a locking device until the matrix of one value has been completely printed and recorded. An indicating device of improved construction co-operating with the counting mechanisms and locking mechanism serves to indicate the actual state of the remaining value of the stamps to be printed.

In order that the invention may be clearly understood, I shall proceed to describe the same with reference to the two forms of construction according to the accompanying drawings, wherein:

Fig. 1^a is a side elevation partly in section.

Fig. 2^a is a cross-sectional view taken on line 2^a-2^a of Figure 1^a.

Figs. 3^a and 4^a are enlarged detail sectional views of parts shown in Fig. 1^a.

Fig. 5^a represents a fragmentary sectional view of a modification of construction.

Fig. 1 shows one half of the casing in side elevation.

Fig. 7 is a corresponding view of the other half of the casing.

Fig. 2 is a plan view of the construction shown in Fig. 1.

Fig. 8 is a plan view of the construction shown in Fig. 7.

Fig. 3 is a front view of the construction shown in Fig. 1, the wall of the casing being omitted.

Fig. 4 is an end view seen from the other side.

Figs. 5 and 6 show the printing cylinder in cross section and end view.

Fig. 6^a is a detail sectional view showing the counter in vertical position.

Fig. 6^b is a detail sectional view of a part of the counting mechanism,

Fig. 6^c is a sectional view showing a part of the gear operating mechanism.

Fig. 9 is a fragmentary side elevational view, partly in section of the printing cylinder,

Fig. 10 is an end elevational view, partly in section of the printing cylinder,

Fig. 11 is a top plan view of a part of the driving mechanism,

Fig. 12 is a front elevational view of the printing cylinder adjusting dial plate,

Fig. 13 is a plan view of the cylinder adjusting handle,

Fig. 14 is a side elevational view of the handle, partly in section,

5 Fig. 15 and Fig. 16 are enlarged fragmentary sectional views showing the type partly within and fully projected from the cylinder, respectively,

10 Fig. 17 is a plan view of an arbor supporting a printing cylinder,

Fig. 18 shows plan and sectional views of an operating cam for part of the mechanism,

15 Fig. 19 is an elevational view of a reversing gear mechanism, and

Fig. 20 is a fragmentary sectional view showing a part of the cylinder rotating means.

20 In the hollow printing cylinder *a* the valve stamp *e* is located and keyed upon the shaft *b* so that it participates in the revolution of said shaft, the value stamp *e* can be either of circular cross section or of prismatic cross section and is engraved upon its circumference or upon the several faces with matrices for stamps of various values and kinds, for instance postage stamps, insurance stamps, revenue stamps or similar indications. The printing cylinder *a* is keyed upon the shaft 25 *c*. Upon the right hand side end of shaft *b* a toothed wheel *d* is keyed which is held in the adjusted position by a locking pawl *g* controlled by a spring *g'*. A toggle lever *i* may be connected with the supports *f* so that the 30 printing cylinder *e* is lowered and brought in contact with the surface upon which the stamp has to be printed, in the manner described in a parent application, by the depression of the toggle lever *i*. The toggle 35 lever *i* is merely diagrammatically shown as its construction and operation are fully described in the parent application. The shaft *c* mounted in the supports *f* so that it can revolve carries the hollow shaft *h* which is 40 movable in lateral direction. Upon this hollow shaft *h* spur wheels *h'* and *h''* are keyed. A pressure spring *t* wound around said hollow shaft *h* inside the drum *a* serves for bringing the spur wheels *h'* and the adjusting disk *t'*, keyed upon the hollow shaft, in engagement with the feed disk *u* arranged upon the shaft *c*. This feed disk *u* has in its inner hollow space adjustable feed teeth *v* which project through the circumference of 45 the disk. Upon the end of the hollow shaft *h* which projects from the casing *A* a handle *B* is arranged which is controlled by a spring *k*. The handle *B* is hollow and encloses the spring *k* which is wound around the shaft *h* 50 and fixed on the same. Upon the outer surface of the wall of casing *A* a star-shaped disk *m* is fixed with the spaces *m''* between the teeth of the same the fork *m'* of the handle *B* engages through the action of 55 spring *k* which bears against the wall *B'* of 60

handle *B* so that the accidental rotation of the handle is prevented. Marks or figures 10, 20, 30 are arranged over each notch *m''* which indicate the stamp value in accordance with the stamp values marked upon the printing cylinder *e*.
70

Upon the left hand side end of shaft *c* a spur wheel *n* is fixed on the drum *a* which meshes with a spur wheel *n'* keyed upon a shaft *n'*. The shaft *n'* mounted in the support *f* carries further upon its other end a counter feed disk *o*. At the side of this counter-feed disk is a hollow shaft *o'* is adjustably mounted upon the shaft *n'* and carries a toothed wheel *p*. As shown in Fig. 80 3 the spring *p'* bearing on axle *o'* and on the other hand on support *f* presses into engagement with the feed disk *o* the adjusting disk *q*, rigidly connected with the toothed wheel *p*. The feed disk *o* has various teeth, 85 incisions or angular pieces *w* upon its circumference of which, according to the adjustment of the handle *B* and in consequence of the form of disk *q* similar to a sector Fig. 4, a determined number are made to project from the circumference of the feed disk *o*. The number disks of the counting mechanism *s* are arranged upon the shaft *r* mounted in drum *a* and said disks are operated by the feed teeth *v* as, at the rotation of the 90 drum *a* the feed wheels *s'* for the counting mechanism *s* mounted on shaft *r* rolls around the stationary feed disk *u* so that it is acted upon by the feed teeth *v* and operates the counting mechanism *s*.
95

The operation is as follows:—

Suppose the printing cylinder *e* has to be adjusted for the printing of a total amount of stamps of a predetermined value. With this object in view the fork *m'* is withdrawn 1 with the aid of the handle *B* from the notches *m''* of the star-shaped disk *m* the hollow shaft *h* with the spur wheels *h'* and *h''* being pulled back at the same time. The spur wheels *h'* and *h''* are thus brought into engagement with the toothed wheels *d* and *p* respectively. At the same time the end face 1 of spur wheel *h'* acts upon the extension *y* of pawl *g* and disengages this pawl from the toothed wheel *d*. By the rotation of the 1 handle *B* together with the hollow shaft *h* the printing cylinder *e* is adjusted through the intermediary of toothed wheels *h'* and *d* to the desired value degree. By the simultaneous bringing in gear of the spur wheel *h''* 1 with the toothed wheel *p* a number of the feed pins *w* and *v* of the feed disks *o* and *u* corresponding to the value degree in question are made to act upon the counting mechanisms through the intermediary of the adjusting disks *q* and *t*. If the adjusting is finished and the handle *B* released the hollow shaft *h* and with the same the spur wheels *h'* and *h''* are returned to the initial positions by the action of the spring *k*. At the rotation of 1

the drum *a* around the stationary shaft *c* and at the printing of a stamp by the printing cylinder *e* the same value as printed is recorded in the counting mechanisms.

5 By the spur wheel *n* keyed upon shaft *c* outside the drum *a* and meshing with the spur wheel *n*² keyed upon shaft *n*', the feed disk *o* is made to revolve at each printing of a stamp owing to the rotation of drum *a*, whereby the feed teeth *w* operate the feed 10 mechanism of a counting device which, according to the adjustment of the printing cylinder *e* is fed by the teeth *w* for the amount of the value of the stamp for which the apparatus has been adjusted. The counting 15 mechanism operated by the drum in synchronism with the above mentioned counting mechanism records also the value of the different stamps printed and prints further upon the surface the actual state of the total 20 amount of the stamps which have been printed. The printing roll *e* prints its stamp at the side of these records.

Fig. 5^a shows a modified construction of 25 the releasing device B which consists in this case of a hand lever *z'* pivotally mounted at *z'* on the support *f* and embracing the hollow shafts *o'*, *h* upon which shafts the spur wheels *p*, *h*², *h'* are keyed. The hand lever 30 *z'* and the spur wheels *p*, *h*², *h'* are held, by the springs *u'* in the normal position of rest, or in engagement with the counter feed mechanisms *o* and *u*. If the lever *z'* is moved to the right for the adjustment of a stamp value 35 the spur wheels *p*, *h*² and *h'* and *d* are brought into gear in a similar manner as above described. The adjustment of the feed teeth *w*, *v* and of the printing roll *e* is effected from the adjusting arms *B''* which are 40 united to form a ring *C* keyed upon the shaft *o'*. The adjusting arms *B''* have marks or figures 10, 20 and so on upon their heads. After the adjustment all these parts return, 45 under the action of the springs, to the initial positions.

Referring to the construction shown in Figs. 1 to 19 the casing of the rolling stamp is composed of two parts X and Y. The part X has hooked-shaped catches 12 (Fig. 7) 50 with which the hooks 21 (Fig. 1) of the part Y of the casing in which the entire driving mechanism is mounted engage if the two parts of the casing are put together. The driving mechanism for the printing cylinder 55 consists of two standards 31 and 31' (Figs. 1, 2 and 3) which are connected with one another by an intermediary piece 32 with connecting screw 34 (Fig. 1). The standard 31' rests upon the part Y of the casing and the 60 rail 31 engages with the guide piece of the part X of the casing if the two parts of the apparatus are being put together (Fig. 4). In order to further secure the support in its 65 position, the standard 31' bearing against the part Y of the casing has a projection 33 which

is locked in a notch of the part X of the casing, so that a variation of the position of the supports for the drive is securely prevented.

The printing cylinder *d'* (Figs. 3, 5 and 6) 70 which is constructed like a capsule 46 is closed by a lid 47. Locking screws 48 (Figs. 5, 6) serve for connecting the capsule and the lid. In the capsule 46 of the printing cylinder *d'* two counting mechanisms 60 to 66 for 75 the stamps printed two mechanisms 91 to 97 for adjusting the stamp values and also the device for altering the stamp value are arranged. The printing types of the counting mechanisms for the stamps printed and 80 of the adjusting devices for the stamp value project through the opening in the wall of the capsule 46. The figure wheels 61 of the counting mechanisms for the stamps printed are mounted upon the axles 62 mounted between the capsule 46 and its lid (Figs. 5, 6). The number wheels are driven in the well known manner by pinions 63 keyed upon shaft 64 and effect in any convenient manner, for instance like a Maltese cross, the 90 feeding of the counting mechanism. The driving of the counting mechanisms for the stamps printed is effected by operation of the feed wheels 65 and 66 of different diameters which have a determined ratio of division 95 to the one with regard to the other. These feed wheels feed the counting mechanism, according to whether the larger wheels 65 or the smaller wheels 66 are operated with the same times of revolution, either for the normal amount of numbers or for the double amount. Toothed locking disks 69 connected with the top number disk 61' are also mounted upon the same shafts 62 upon which the wheels 65, 66 are keyed. Blade springs 67 100 slide one upon each of said locking disks (Fig. 5) in order to regulate the uniform revolution of the figure wheels, said blade springs being mounted upon hollow axles 68 telescoped upon the driving axles 64. 110

The driving of the wheels 65, 66 is effected through the intermediary of the driving wheels 110 of the counter. Upon the stationary axle 49 of the stamping roller a casing 71 for a tooth chain is fixed by means of studs 72 or the like (Figs. 6^a and 6^b). The teeth 77 which in each half of the casing are combined to form a chain 76 project through slots 74 and engage with the drive wheels 110 which control the counting mechanisms (Fig. 6^a). The end of each member 77 of the chain which projects through the corresponding slit 74 of the casing is formed like a tooth but the other part of said member, situated inside the casing, forms in one direction a fork 77' and in the other direction a flat perforated extension 77''. The several teeth are mounted successively in such a manner that each extension 77'' engages always 125 with a fork 77' of the preceding tooth with 130

which it is connected by a hinge pin 78 so that the teeth 77 are united to form an articulated chain 76. A hollow axle 80 is mounted on the shaft 49 (Figs. 5, 6, 6^a and 18) and upon the part of this hollow axle 5 which terminates inside the casing 71 for the tooth chains, the eccentric 79 is keyed. The faces 79' of the eccentric 79 are, at the position of rest, out of contact with the two 10 chains 76 but if the eccentric is being operated, a number of teeth 77 are advanced through the slits of the casing which correspond with the value of the stamp for which the apparatus is adjusted so that these teeth 15 are securely held in this position. Two locking faces 75 for the counting mechanism of the stamps printed are arranged on the periphery of the casing 71. These locking faces 75 bear at the moment of the printing, 20 or in any other desired position of the printing cylinder, against the locking disks 69, whereby the accidental or intentional rotation of the figure wheels is prevented (Figs. 5, 6.)

25 For each counting mechanism of the stamps printed a corresponding mechanism for the adjustment of the stamp value is arranged. The stamp value rollers 91 (Figs. 5, 6 and 17) serve as carriers for the several 30 stamp values which can be provided in any convenient manner. The surfaces of these rollers 91 are divided into as many sections as stamp values are to be provided. One group of stamp values can for instance comprise the numbers 1-10, the next following group the numbers 11-20 and the third group of numbers 21-30. According to whether the one or the other of the groups of stamp values are adjusted for operation, numbers 35 of a higher or lower value will be printed. The axles 92 of the rollers 91 are journalled in the walls 46, 47 of the printing cylinder d'. Upon each axle 92 a toothed wheel 94 is keyed which serves as drive (Fig. 17). A spring 40 95 mounted upon the corresponding axle 92 (Fig. 17) serves for regulating the uniform rotation of the stamp value rollers 91 by sliding upon the bottom surface of the capsule 46 so that at the adjusting of the rolls 45 91 the centrifugal action of said rolls is braked. After the stamp value rollers have been adjusted for a determined number they are locked in their position by means of a locking member 97 (Figs. 5, 6^a and 18) rotatable around the shaft 80 and having locking claws 97' designed to engage with the teeth of the drives for the stamp value rollers. 50 With this object in view the locking member 97 is telescoped on shaft 80. Its ring-shaped bush, constructed to form a bearing surface, is rotatably mounted on the feed-wheel 82' and the locking claws 97' engage with the toothed wheels 94. If the member d' revolves the locking member 97 participates in this revolving movement revolving

in its ring-shaped bush rotating above the stationary adjuster 82 supported by the toothed wheels 94. If the rollers 91 marked with the groups of stamp values are being adjusted, the locking member 97, which is situated directly above the adjuster 82 must be raised together with this adjuster which is raised by shaft 80 so that the claws 97' get out of engagement with the toothed wheels 94. If the adjuster 82 returns to the position of rest, the locking member 97 with the claws 97' is brought back to the initial position by the action of the springs 95 mounted on the axles 92.

Upon shaft 80 the adjuster 82 (Figs. 5, 6^a, 18) having a toothed segment 82' is keyed which serves for rotating the rollers 91 so that they print a stamp of determined value.

The simultaneous adjustment of the feeding devices for the counting mechanisms so that they correspond with the stamp values adjusted is effected by a reversing device. Between the capsule 46 and the lid 47 the reversing axles 109 are mounted upon which the toothed driving wheels 110 for the counting mechanism are keyed (Fig. 6^a). Upon the guide face 109' of the axles 109 flattened above the wheels 110, reversing wheels 110 and 111 (Fig. 19) are mounted which are adapted to be raised and lowered and which stand the one over the other (Fig. 19). Reversing forks 106' of the reversing lever 106 (Fig. 5) engage with the guide collars 113' of the guide bushes 113. The reversing lever 106 rests with its bearing face, on the one hand, upon the ringshaped bearing 115' of the shifter 115 and it is mounted on the other hand with its guide bushes 108 in the columns 107 arranged between the capsule 46 and the lid 47 so that it can be moved in vertical direction (Figs. 5 and 18). The shifter 115 is adapted to be displaced in lateral direction between the segments 81 upon the adjusting shaft 80 (Fig. 5). Upon the extension 33 a curve-ring 117 is arranged (Fig. 14) against which the curved member 116 revolves, this member being removably fixed upon the shifter by means of screws. Upon the part of the adjusting shaft 80 which projects from the wall of part y of the casing the adjusting lever 124 is fixed by means of a stud 118 or the like (Figs. 3 and 12-14). The handle 124' of the adjusting lever has a hand 124'' which moves over the notches 127 of the adjusting scale 126 fixed by screws 126' upon the casing y said notches 127 indicate each a determined stamp value. Upon the plate 35 a base plate 143 is fixed for a counting mechanism (Figs. 1, 2, 11) which is visible and is fixed by means of screws so that it can be easily removed. In the casing 136 of the counting mechanism the figure wheels 137 which are operated in the well known manner by feeding pinions revolve around the 130

shaft 140 which in its turn is driven by the toothed wheel 141 (Fig. 1).

For the object of feeding the visible counting mechanism a casing 152 for a tooth chain is fixed by means of a screw 153, or the like upon the shaft 151 journalled in the members 31, 31' (Figs. 1, 3, 9, 10, 15, 16). The casing 152 has four slits in its surface of which two are juxtaposed in each half of the casing. The teeth 157 of the chain which have in the manner above described each a fork 159 and a hinge pin 160 project also through these slits 154, the chain 155 carrying double the number of teeth 157, 157' as the chains 156. An adjusting eccentric 162 connected with its support 161 movably mounted upon shaft 151 is pushed into the casing of the chains and serves for closing said casing by its rim 162'. Shaft 151 is enclosed in a sleeve 161'. A pressure spring 163 bears against the closing disk 161'' keyed on sleeve 161', and fixed on shaft 151 by means of a pin 151', said spring pressing the eccentric 162 into the chain casing 152 and ensuring thus an always uniform mounting of the same. The rotation of shaft 151 and consequently of the entire feeding device for the visible counter is effected together with the movement of the printing cylinder *d'* by means of the toothed wheel 164 mounted upon this roller and participating in the movement of the same and further by means of the counter toothed wheel 165 meshing with the toothed wheel 164 and securely coupled with shaft 151 (Figs. 1, 5, 6). For limiting the working of the counting mechanism a locking device is used in the well known manner (Figs. 1, 2, 11). Upon the plate 143 (Fig 1) the angle iron 171 is arranged. In the arm 171 opposite to the fixing point and forming a bearing block, an axle 172 is journalled upon which the angular toothed wheel 173 is mounted by means of a stud 173' or the like (Figs. 1, 2, 11) the teeth of this angular toothed wheel meshing constantly with the toothed wheel 138 of the extreme figure wheel 137'.

The axle 172 is further journalled in the angle iron 174 fixed on plate 143 and embracing shaft 140. Above the angular wheel 173 the locking disk 175 with the locking scale 175' is connected by a pin or the like with the locking shaft 172. Over this locking disk 175 the carrier 177 for the locking lever is mounted upon shaft 172 so that it can be displaced in upward and downward direction. The carrier 177 carries at its lower end the locking lever 177' adapted to engage with the corresponding locking notch of the locking scale. The carrier 177 is guided at its head 177'' and it is held by means of a pressure spring 178 located in the hollow carrier 177 and wound around the shaft 172 so that the locking lever is secured in its engagement with the corresponding notch.

After the amount of stamps determined by the locking scale 175 has been printed the

locking lever acts upon the locking lever 186 for the driving gear (Figs. 1 to 3). Upon the intermediary piece 32 the bearing consisting of an angle piece 187 for the lever 186 is arranged the journal 190 of which revolves in the upper piece 187 and is connected at the middle with a fork-shaped connecting lever 192 the perforated fork-shaped ends 192' of which embrace on the one hand the locking lever 186 with which they are movably connected by screw 193 or the like, and on the other hand the angular abutment 195 with which they are hingedly connected in a similar manner by a screw 194 or the like. The angular abutment 195 rests with its bearing surface which forms a bearing column 195' and with journals 195'' in the connecting piece 32 so as to form a double angular bearing. The locking lever 186 acted upon by the locking lever 177' of the counting mechanism places itself with its angular abutment 195 in front of the locking flange 198 for the driving gear keyed upon an extension of the counter toothed wheel 165 (Fig. 9), a stud 198' or the like ensuring the connection between the locking flange 198 and the counter toothed wheel 165. The pull spring 197 wound around the angular abutment 195 and fixed upon the double angle piece 196 by a stud 197' or the like serves for returning the locking lever 186 from the locking position into the position of rest.

The uniform rotation of the several stamping faces of the printing cylinder *d'* is ensured by a regulating device (Figs. 1 to 3). Upon the inner side of the part X of the casing at the left hand side in front of the printing cylinder a sliding rail 211 is arranged in which a sliding carriage 213 is mounted which is adapted to be displaced in upward and downward directions. A guiding lever 217 is mounted upon the journal 218 fixed upon the sliding carriage 213, one end of said lever forming a locking abutment 217'. A spiral spring 219 held at one end by a pin 219' or the like engages with its other end the guide lever 217 and forces the same into the initial position limited by the stop pin 220 of the casing *y*. Upon the guiding the rail 211 a supporting piece 221 is arranged and fixed by means of a screw 222. This support 221 has a pin 227 around which the lever 224 oscillates which has an extension 225. A pull spring 228 is attached on the one hand to a pin 226 fixed upon the angle lever 224 and on the other hand to a pin 230 fixed at the upper end of the carriage 213. The carriage 213 supports in its part which projects through an aperture *d''* at the lower end of the apparatus upon a journal 216 a revoluble wheel 215 which, if the apparatus is placed upon the surface to be printed, raises the carriage. The printing cylinder *d'* has locking pins 53 on the lid 47.

In order to ensure that the mechanism can

be adjusted from one stamp value to the other only after one stamp has been completely printed a special device is provided which consists of a locking pawl 214 mounted upon the carriage 213 which pawl slides over the 5 rim of the lid 47 of the printing cylinder d' when this cylinder is rotated and engages under the action of spring 228 within a corresponding notch 52 (Fig. 1) only if one rotation of the cylinder has been completed. The back rotation of the printing cylinder d' and consequently a fraudulent re-using of the stamp which has already been printed, is prevented by a device which locks the cylinder d' 10 against back-rotation (Figs. 1 to 3). Upon the connecting piece 32 a locking tooth 246 having two noses is fixed by means of a screw 248 and pressed by the action of a pressure spring 249 between the teeth of the counter- 15 actuating toothed wheel 165 so that it prevents the back rotation of this wheel. The inking of the printing cylinder d' is effected by an inking device (Fig. 7). With this object in view a casing 256 is arranged on the front 20 face of the apparatus and an ink tube 258 is arranged in said casing which ink tube has nozzles and is surrounded by a number of juxtaposed lamellæ 259. An inking ribbon 261 is placed upon these lamellæ. A locking 25 wheel 264 is arranged around the inking tube 258. A locking pawl 265 has a nose 265' which engages with the locking wheel 264. At the upper part of the casing 256 a lever 265 is pivotally mounted by means of a screw 30 263, a screw 267 serving to fix the lower part of said lever. A spring 266 of lever 265 engaging with a nozzle 267' and also with a nipple 263' of lever 262 serves to pull said lever 262 downward so that it bears against 35 the inking roll and presses the same against the printing cylinder d' . Behind the printing cylinder d' the lower part x' of the wall of the casing X is bevelled in order to prevent that the stamps printed be blurred when 40 the printing cylinder is rolled over the paper. The printing cylinder is protected by a closing device (Figs. 1, 3, 7, 4). A T-shaped double angle 295 is pivotally mounted upon a pivot pin 296 of the part X of the casing 45 and has in its head a guide screw 297 which projects through a slit 297' of the part X of the casing and has an extension 297' provided with an eye which grips at the closing position over the closing cramp 15 into which a 50 padlock or the like can be inserted. The double angle 295 has upon its lower arm a guide pin 298. A supporting lever 301 is mounted with both arms 301' upon the axle 151 and movably connected by means of a 55 connecting screw 300 with the transmission lever 299, the slot 299' of which serves for receiving the guide pin 298. The straight arm of the transmission lever 299 is also movably mounted by means of a screw 303 in a sup- 60 porting wall 302' of the locking bow 302. 65

The two supporting walls 302' are terminated by lugs 302'' by means of which they are suspended upon the shaft 49 and 80 so that the bow-shaped part 302 encloses part of the printing cylinder d' . 70

The operation is as follows:—

Suppose the printing cylinder has to print a stamp of the value "50". In this case the shaft 80 has to be pulled out by means of the handle 124' so far that the value indicating hand 124'' may be turned up to the notch "50" to be inserted in the same. When the shaft 80 is being pulled out the claws 97' of the locking member 97 are at the same time lifted out of the pinions 94 of the value rollers 91 and the toothed segments 88' of the feed wheel 82 are brought into engagement with the pinions 94. The feed wheel 82 mounted upon the shaft 80 participates in the revolution of said shaft and adjusts the value indicating rollers connected with it by the toothed wheels 94 to the figure corresponding with the value "50". At the same time the feeding devices for the stamp counting mechanism are adjusted. The eccentric 79 at the end of the shaft 80 is thus made to act upon the different teeth 77 of the toothed chain 76 and if one tooth advances at the feeding with one number in the counting device, it must push through the slits 74 of the casing a number of teeth corresponding to the adjustment, in the present case five teeth. The stamps produced by the apparatus must however not print only the actual value and the number of the stamps which have been printed or the total value of these stamps but also the printings must be further visibly recorded with the aid of one or several counting mechanisms. The counter 136 with driving pinion 141 is for instance provided for the visible recording of the total value of the stamps which have been printed, the indications of this counter 136 appearing in a window. The driving wheel 141 keyed upon shaft 140 is driven by a feeding device 151—161 which is mounted in the casing 152 of the tooth-chains 155 and 156 and the eccentric of which acts upon the tooth chains 155, 116 in the manner as described with reference to the feeding device 71—82 for the counting mechanism for the stamps printed. The adjustment of this device for the visible counting mechanism is effected from the shaft 80 at the same time as the adjustment of the feeding of the counting device and of the rollers 91 for the values printed. 95 With this object in view a toothed wheel 119 is arranged upon the shaft 80, which, by the intermediary of the toothed wheel 121 mounted upon the standard 31' operates the toothed wheel 123 connected with the eccentric 162 (Figs. 1, 3, 9). According to the adjustment on the adjusting scale 126 the eccentric 162 will be revolved by the toothed wheel 123 so that its rim 162' slides relatively to the casing 152 and brings the corresponding number 100 105 110 115 120 125 130

of teeth 157 and 157' into engagement with the driving gear for the visible counting device by making the same project through the slits of the casing 154. The pressure spring 5 mounted in the support 161 of the eccentric maintains the eccentric constantly in proper position in the casing. The number of the teeth in the casings 71, 152 for the tooth chains can be arranged as desired. The possibility to increase the effect of these teeth if 10 the same number of teeth are used is provided by the arrangement of a separate adjusting device. In this case the effect of each single tooth is for instance increased in such 15 a manner that the tooth counts, owing to the adjusting device for two figures. In the form of construction shown by way of example the adjusting device is constructed as follows:—

20 If the adjusting eccentric 79 has advanced all the teeth 71 in consequence of the handle 124' having been operated for the lowest group of values, said eccentric at the adjusting for the next higher group of values, 25 will be brought out of contact with the tooth chains by a further rotation of the shaft 80 and moved to the first tooth of the second tooth chain in the casing 71. Simultaneously the toothed segments 82' of the feeding 30 wheel 82 of the stamp value indicator have at the rotation of shaft 80 got out of engagement with the driving wheels 94 of the value roller 91 and after the idle movement caused by the part between the two toothed segments 35 82' the first tooth of each toothed segment 82' is ready again to act upon the feeding wheels 94 after, by the last tooth of each toothed segment 82', the rollers 91 have been revolved so that they indicate the next higher 40 value group. At this idle running of the adjusting eccentric 79 from one tooth chain to another as well as of the feeding wheel 82 the adjusting cam 116 which is fixed upon the shifter 115 moving between the guide segments 81 of shaft 80 has moved over the 45 ascending curve formed by the counter-ring 117. As the adjusting cam 116 is fixed upon the shifter 115 and as the counter-ring 117 is fixed upon the shoulder 33 of the bearing, 50 the shifter 115 must at the ascension of the cam displace itself outwardly so that it lifts by means of its ring 115' the lever 106 (Figs. 5, 6). The two forks 106' of the lever 106 embrace in the guide slots 113' the guide 55 bushes 113 of the large wheels 112 and of the small wheels 111 mounted upon the axles 109 lifting the small wheels 111 out of the large feeding wheels 65 for the counting mechanism and bringing the large wheel 112 60 into engagement with the small feeding wheel 66 of the counting mechanism.

Before the adjusting the wheel 111 was in gear for the feed wheel 65 of the counting mechanism. If in this position the printing cylinder *d'* has been revolved through 65

the intermediary of the shaft 49, the toothed wheel 110 would have been rotated by the teeth 77 when passing along the stationary casing 71. The toothed wheel 111 mounted on the same shaft 109 as toothed wheel 110 transmitted its movement upon the toothed wheel 65 which in its turn operated the counter 61 for the printing operations. The toothed wheel 111 has with regard to toothed wheel 65 such a ratio of division that each 70 movement caused by one tooth through the intermediary of toothed wheel 110 effects in the counter 61 the advance of one figure of the number disk of the lowest value. After the adjusting the toothed wheel 65 is no longer 75 in gear with the toothed wheel 111 of the same ratio of division but the large toothed wheel 112 is in gear with the small toothed wheel 66. The ratio of division of these two wheels 80 112 and 66 is such that the rotation of wheel 85 110 effected by one tooth 77 produces, owing to the altered ratio of transmission for the same time unit, a movement of toothed wheel 66 for the double amplitude and consequently the advance of the number disk of 90 the lowest value in the counter 136 for two figures.

The feeding device for the mechanism for the visible counting may also be adjusted for the increased action of the feed teeth, this 95 being effected either in the manner which has just been described or by mounting in the casing 152, besides the two tooth chains 156 with normal feeding effect of which one tooth 157 of each chain serves to advance the 100 counter 136 for one figure, two toothed chains 155 with a double number of feeding teeth 157'. The arrangement of the tooth chains 155, 156 is in this case so that in one half 105 of the casing 152 the normal chain 156 is mounted upon the inner wall, and the double chain 155 upon the outer wall and that in the second half of the casing the normal chain 156 is mounted upon the outer wall and the double chain 155 upon the inner wall. 110 The chains are therefore displaced in both halves of the casing the one with regard to the other. The two eccentrics 162 in the casing 152 are also mounted upon the support 161 displaced the one with regard to the other. 115 Each eccentric can operate in one half of the casing only the one, the simple chain 156, or the other, the double chain 155.

When the shaft 80 is pulled out by means of the handle 124 for adjustment the tooth 120 wheel 119 keyed on said shaft comes in gear with the toothed wheel 121 which is loosely mounted on a shaft 122 and which is permanently in gear with the toothed wheel 123. By the putting in gear of toothed wheel 119 125 these three toothed wheels 119, 121 and 123 are connected the one with the other to form one gear. If the handle 124' is now turned, which means that it is adjusted for one value group, the toothed wheels 119, 121 and 123 130

- are rotated at the same time so that toothed wheel 123 drives the eccentric 162. The ratio of transmission of these three toothed wheels is arranged so that in accordance with the 5 value group adjusted on the value roller 91 the required number of teeth 157 or 157' are made to advance through the slits 154 of casing 152 by means of the eccentric 162. The teeth 157 will then rotate each for one figure 10 through the intermediary of pinion 141 the number disk of the lowest value of counter 136. At the transmission of the value roller 91 to a higher value group the eccentric 162 has evidently participated in the rotating 15 movement transmitted by the toothed wheels 119, 121, 123. At this occasion the eccentric 162 has gone away from the simple chain 156 and comes in engagement with the double chain 155 in the other half of the casing 20 152, so that the eccentric will now make advance along a double tooth 157' of chain 158. One double tooth 157' effects however the advance of two figures in the counter 136, so that in conformity with the adjustment 25 of the counting mechanism for the stamp printed the effect of the visible counting mechanism is correspondingly increased. At the reverting to the normal action of the teeth the simple chain will be put again in 30 gear in the visible counting mechanism and in the counting mechanism for the stamp printed the descending cams 116, 117 will push the shifter 115 back into its initial position. 35 At the same time the large reverting wheels 112 of the feeding gear for the counting mechanism for the printed stamps disengage from their pinions 66 and the small reverting wheels 111 are brought again in engagement 40 with their pinions 65. It is evident that by modification of the ratio of transmission of the driving wheels 65, 66, 111 and 112 with regard to one another any increase of the effect of the existing feeding devices can be 45 produced.
- If now the printing cylinder, after the feeding devices have been adjusted rolling on the stationary shafts 49, 80, there are printed, besides pictures, figures or inscriptions, the 50 number which on the value roller 91 indicates the value of the stamp and further from the counting mechanism 61 the total of the stamps which have been printed. If the printing cylinder prints for instance postage 55 stamps and if the post office which lets the apparatus has determined a limit amount for which stamps can be printed, the post office can see from each printed stamp how much has been used of the amount. This control is 60 very useful for the post office prepaid total as well as for the use of the apparatus. During the revolving of the printing cylinder the driving wheels for the counting mechanism move over the adjusted teeth 77 projecting from the stationary casing 71 on axle 49, 65 are advanced by the same and operated by their reverting wheels 111 or 112 the feed wheels 65 or 66 of the counting mechanism. These feed wheels rotate in the well known manner through the intermediary of the pinions 63 mounted on the axles 64 the number disks 61 in accordance with the number of the adjusted teeth. After the feeding, the locking disks 69 connected with the upper disk 61' slide upon the locking faces 75 and prevent thus the rotation of the number wheels 61 (Figs. 5, 6, 6^a). The toothed wheel 164 fixed upon the printing cylinder *d'* revolves with the same and engaging with the counter toothed wheel 165 keyed upon the shaft 151 makes this shaft revolve so that the teeth 157 or 157' of the casing 152 are made to operate also the driving gear 141 for the visible counting mechanism 136.
- As previously described the visible counting mechanism has in the well known manner a locking device which locks the counting mechanism as well as the driving gear connected with the same as soon as any determined number is reached.
- In the course of the printing the device 141 is rotated by the teeth 157 or 157' and the number disks 137 are rotated or advanced in the manner known from counting mechanisms. With the number disk 137 which has the highest figures a toothed wheel 138 is connected so that it rotates with the same. In the form of construction shown in Fig. 11 the number disks 137' serves for the thousands.
- If in course of the printing this number disk 137' has rotated for one figure the angle wheel 173 which is in permanent gear with toothed wheel 173 is rotated as well as its axle 172. In this rotation participates the locking disk 175 keyed on axle 172 and the locking lever 172' of the same. This locking disk 175 has ten notches 175' which means that the locking disk 175 is divided into ten units in a similar manner as the number disk 137' and that each notch 175' from 0 to 8 corresponds with one figure of the number disk 137', said locking disk 175 being thus rotated in accordance with the number disk 137 for one unit of the thousands. If in course of the printing the counting mechanism arrives at the predetermined figure at which the apparatus and the counting mechanism have to be locked, the lever 177' engaging with the scale 175' acts upon the lever 186 designed to lock the driving wheel 165. If the locking lever 177' has for instance been made to engage with the number IX of the locking disk 175, as shown in Fig. 2, it must operate the lever 186 at the instant 125 when the number disk 137 is revolving from figure 8 to figure 9, that is to say from number 8000 to number 9000.
- The lever 186 pushes with the aid of the connecting lever 192 fixed upon it the angular 130

abutment piece 195 pivotally mounted in a column-bearing 195" into the path of the locking flanges 198 which turn together with the toothed wheel 165 around the axle 151 and are locked by the angular abutment 195.

After the locking lever 177' for the counting mechanism has been released from its locking position in the form of construction shown from notch IX the locking lever 186 for the drive gear returns under the action of the pull spring 197 to the initial position and releases thus the locking flange 198 and consequently the driving gear. Owing to the locking disk 175 it is possible to extend the locking limit to a desired value before the locking of the counting mechanism begins so that it is not necessary to wait for the locking taking place before the locking device can be re-adjusted.

The person who uses the apparatus can read from the counting mechanism 136 the actual state of the value of the stamps printed but he cannot ascertain how many stamps can still be printed. The following device serves to obviate this inconvenience:—

The head 177" of the support for the locking lever of the locking system for the counting mechanism carries a mark 176 (Fig. 8). Around the head 177" projecting through an aperture of the lid 6 of the apparatus a circle of figures from 9 to 0 (Fig. 8) is arranged upon the upper surface of the casing X and the head of the support of the locking lever rotates in this circle simultaneously with the locking disk 175 so that the mark 176 indicates always the number which corresponds with the total value of the stamps which are still to be printed.

In the example shown in Fig. 2 the lever 177' stands over the figure IX as the number at which the apparatus has to be locked. Suppose the number disk 137' has just moved from 7 to 8 or from 7000 to 8000; in this case stamps for the value of 1000 may still be printed before the apparatus is locked. This is indicated by the mark 176 pointing to "1" which is equal to "1000". When the number disk 137' has rotated to the figure "9"="9000" this mark 176 will point to "0" in the indicator 2 indicating thus that the amount for which the apparatus has been adjusted is exhausted.

The several stamping faces of which any number can be arranged upon the printing cylinder d' are limited by a locking device 211, 230 (Figs. 1, 3, 9).

The several sections upon the surface of the roll d' are limited by the stops 53 (Fig. 6) arranged upon the capsule 47. When the apparatus is being placed upon the surface to be printed, the wheel 215 raises the sliding carriage 213 connected with the same and moves the guide lever 217 of said carriage towards the locking lever 224. Shortly before a division of the surface of the roll d' has

been completely printed the stop 53 comes in contact with the guide lever 217, which, if the revolving of the roll d' continues is oscillated around its pivot pin 218 so that the projection 225 of the lever 224 which lever is operated by the stop, stands directly above the abutment 217' to be finally pressed against this abutment by the stop 53. The stop 53 is now prevented from oscillating the lever 224 around its axle 227, the stop 53 being thus arrested so that the printing roll d' is locked against revolving after the division has been completely printed.

When however the apparatus is lifted off the surface to be printed the wheel 215 looses its support and the sliding carriage 213 returns with its guide lever 217 to the initial position under the action of the pull spring 288. At the same time the guide lever 217 is swung back by the action of spring 219 into the position of rest limited by stop 120. At the renewed operation of the printing cylinder d' the stop 53 which has previously stopped the movement of the roll can now make the lever 224 oscillate from its path so that it can pass along this lever. The lever 217 has not been acted upon by the stop 53 this time so that it is still in its position of rest outside the path of the stop 53 and of the abutment 225.

The locking pawl 246, the locking noses 246' of which engage with the teeth of the toothed wheel 165, prevent the back rotation of the printing cylinder and consequently also the repeated use of the stamping faces without registration of this use. A safety device prevents that, after the printing of the stamp, the feeding devices for the counting mechanism are adjusted fraudently to a lower stamp value than at the beginning of the stamping. With this object in view a locking pawl 214 is arranged at the upper end of the carriage 213, said pawl sliding upon the rim of the cover 47 (Fig. 1). The carriage 213 is thus lifted always so far that part of the carriage and of the running wheel 215 stands between the driving wheel 119 and the wall of the casing y. It is thus impossible to displace the shaft 80 laterally together with the adjusting lever 124'. Only if all the stamp faces have been used the locking pawl 214 descends and engages with a locking notch 52 of the rim of cover 47. At the same time the carriage 213 and with it the running wheel 215 are lowered by the action of spring 228 for an amount which is equal to the depth of the locking notch. The driving wheel 119 for the adjustment is thus released by the carriage and by the running wheel and the adjusting to a new amount of stamping values can be effected.

The inking of the printing cylinder d' is effected from the inking roller 261 which is pulled against the printing cylinder d' by pull strings 266 acting upon the levers 262 in

which said ink-holder is mounted. Around the ink-tube 260 which has the nozzles a desired number of lamellæ 259 are arranged, between which the ink is stored which has been filled into the ink tube. An inking ribbon 261 encloses the lamellæ so that only so much ink is uniformly transmitted by the ribbon as is used by the printing cylinder d' . If the casing 256 of the inking device is being removed from the apparatus, the locking pawl 265 slides off the rail 18 and engages under the action of a spring 266 automatically with its tooth 265' in an indentation of the locking rim 264 of the inking roller. The closing device 260' of the inking tube can now be removed without the inking tube 260 being held during this operation. The two halves X and Y of the casing of the apparatus can be connected by convenient locking means. With this object in view a screw bolt 23 guided in angle pieces 22 can be used which is secured on part Y in a clamping nut 9 (Fig. 1). Upon the part X of the casing an angle iron 10 with screw 11 and lug 10' 25 for a lead seal can be provided in connection with an angle iron 24 on part Y of the casing (Fig. 7).

In order to avoid that for the adjusting of the locking devices 175—177 for the counting mechanisms the locking means 10, 11, 21, 22 have always to be unlocked and locked, a separate locking device is provided for these parts of the counter which consists of a cap 6 mounted in hinges 7 and having a locking bolt 61 and a lock 281 mounted on sockets 32 and 282. The cap 6 can be locked and unlocked easily by means of the lock 281 (Figs. 1, 7, 8).

A locking device can further be provided for preventing the use of the printing cylinder d' , said device consisting either of a lid arranged over the recess d of the printing cylinder or of an envelope which encloses the printing cylinder partly or entirely, or the locking can be arranged as shown in Figs. 1, 2, 3, 4, 7 and as will be hereinafter described.

The locking bow 302 projects at the locking position into the recess d'' of the printing cylinder d' and embraces the latter the projection 297' of the guide screw 297 bearing against the angular locking piece 15 where it is secured by a padlock 15' or the like so that the bow 302 is secured in its locking position and the use of the printing cylinder d' is prevented. If this device is unlocked the guide pin 297 is moved along the guide slot around pin 297' together with the angle piece 295 swinging around pin 297 so that it is in the open position. The T-shaped angle piece 295 moving thus along a curve, the arm which carries the guide stud 298 is lifted also in radial direction and in ascending it forces the transmission lever 299 to follow its movement. This transmission lever 299 which is connected with one of the

supporting walls 302' and is guided by the supporting lever 301 which is pivotally mounted upon it, raises also the supporting wall 302' and makes the locking bow pivot around the shafts 49, 80 so that it gets out of the locking position. The printing cylinder d' is thus released for use. If the locking bow 302 returns from the open position into the locking position the movements of this locking device are repeated in reverse direction and with reverse effect. 70 75

At the front end as well as upon the side on which the adjusting lever 124 is mounted marks or hands 5 or 4 are arranged which indicate at which place of the surface to be printed the stamps have to be printed according to length or width so that the proper utilization of a determined surface to be printed is ensured. 80

In the machines of the type described which are electrically operated the date of printing the postage stamp, etc., are printed by a printing cylinder which has to be exchanged each time a stamp of another value has to be printed. Instead of this simple printing cylinder designed to print only one stamp value, the above described printing cylinder d' for the printing of stamps of different values may be used alone or together with all the accessories. 85 90 95

The printing cylinder may also be arranged in front of an axle of a crank, the surface to be printed being conducted in the well known manner between the two rollers.

I claim:—

1. A rolling stamp for printing value stamps comprising in combination a casing, a stationary shaft in said casing, a hollow printing cylinder revolubly mounted on said stationary shaft, counting mechanisms in said printing cylinder for recording the stamps printed, matrix printing rollers in said printing cylinders for printing stamps of different determined values, a counting mechanism in said printing drum for recording the values of the stamps printed and for printing the total value of a stamp printed, articulated chains comprising feed teeth for operating said value counting mechanism, an adjusting mechanism for adjusting the matrices in the value printing rollers according to the value of the stamp to be printed and for adjusting the feed teeth of said chains in accordance with the increased stamp value, a locking device for said adjusting mechanism for the stamp values designed to permit the adjusting of the value rollers only after the complete revolution and recording of the printing drum, a locking device for the counting mechanism, a device connected with said locking mechanism for indicating the unused amount of the value limit, a mechanism for limiting the rotation of the print- 100 105 110 115 120 125 130

ing cylinder and a locking device for securing the printing cylinder in its casing.

2. In a rolling stamp of the type described the combination of the casing, a printing drum in said casing, value rollers in said printing drum, counting mechanisms in said printing drum each comprising figure disks and a feed toothed wheel, a totalizing counting mechanism with visible indicating disk, two axles in said casing, toothed feed disks one on each axle, and adjustable feed teeth of said disks meshing with the toothed feed wheels of the countink mechanism in the drum and with said visible counting mechanism.

3. In a rolling stamp of the type described in combination with the casing, a stationary shaft in said casing, a drum on said shaft, a hollow shaft movably mounted in said stationary shaft, a spur wheel on the left hand end of said stationary shaft, a revoluble shaft in said casing above said drum, a spur wheel on the left hand end of said revoluble shaft meshing with the first mentioned spur wheel, a counter feed disk on the right hand end of said revoluble shaft, a hollow shaft upon the right hand end of said revoluble shaft outside said counter feed disk, a toothed wheel on said hollow shaft, an adjusting disk in the form of a sector rigidly connected with said toothed wheel, a spring for holding said adjusting disk in engagement with said counter feed disk, adjustable teeth in said counter feed disk adapted to be made to project from said feed disk by the action of said adjusting disk, a handle on the outer end of a hollow shaft on the stationary shaft, an adjusting disk on said stationary shaft, a spring-controlled toothed wheel on said hollow shaft on the stationary shaft, feed teeth adjustably mounted in said adjusting disk on the toothed shaft of the stationary shaft adapted to be brought into operating position by means of said toothed wheel and its adjusting disk.

4. In a rolling stamp of the type described the combination of a casing composed of two parts, a driving mechanism in one of the parts of the casing, a standard in each part of the casing, a stationary axle in said casing, a screw for securing said axle in the said standards, a printing drum mounted on said stationary axle and having the shape of a capsule, a lid closing said capsule shaped drum, two counting mechanisms for the stamps printed, two mechanisms for stamps of different values and a mechanism for adjusting said mechanism for the stamps of different values, all four mechanisms located in said drum.

5. In a rolling stamp of the type described in combination a casing, a stationary shaft in said casing, a printing cylinder revolvably mounted on said stationary shaft, axles in

said printing cylinder, figure disks on said axles each set of figure disks forming one counting mechanism, pinions for operating said counting mechanisms, feed wheels on said axles for the counting mechanisms, locking disks one connected with the top figure disk of each counting mechanism, a chain casing on said stationary shaft having slits, teeth chain in said casing, two locking faces on the periphery of said chain casing designed to act upon said locking disks of the counting mechanisms for locking said counting mechanisms after each feed movement.

6. In a rolling stamp of the type described in combination with the casing, a stationary shaft, a drum on said stationary shaft, printing rollers in said drum, counting mechanisms in said drum, a chain casing on said stationary shaft having slits for the teeth of the chain, teeth chains in said chain casing for operating said counting mechanisms consisting of members the outer part of which has the shape of a tooth, a fork-shaped rear end of said member and a flat perforated extension of the same the extension of one member engaging between the fork-shaped part of the following member, a hinge-pin for connecting said extension and said fork-shaped part of two concentric teeth, an eccentric in said chain casing designed to act upon said tooth chain so that a part of the teeth are made to project through said slits of the chain casing to operate the counting mechanisms, the remainder of the chain being slack in its casing.

7. In a rolling stamp of the type described a mechanism for locking the stamp value rollers in their actual position comprising in combination a printing cylinder, axles journaled in the walls of said printing cylinder, stamp value rollers one on each of said axles, springs one on each axle for regulating the uniform rotation of said stamp value rollers, toothed wheels one for each stamp value roller serving to drive said rollers and a toothed locking rail rotatable on said hollow shaft designed to engage with said driving wheels of the stamp value rollers.

8. In a rolling stamp of the type described the adjusting mechanism for the stamp value rollers, comprising in combination a printing cylinder, stamp value rollers on said printing cylinder, toothed wheels one for each stamp value roller, axles mounted in said printing cylinder one above each stamp value roller each axle having a flattened part, large reversing wheels movably mounted on said flattened parts of said axles, small reversing wheels on said axles, a hollow shaft in said printing cylinder, a shifter on said hollow shaft, a ring-shaped bearing of said shifter, a reversing lever movable in vertical direction so that it is adapted to move around said shifter.

9. In a rolling stamp of the type described,

a feeding device designed to ensure that the mechanism of the rolling stamp can be adjusted for another stamp value only after all the corresponding stamps have been printed 5 comprising in combination, a main casing, a printing cylinder in said main casing, a lid of said printing cylinder, a projecting rim of said lid having a notch, a guide rail in said main casing, a sliding carriage guided on 10 said rail, a locking pawl on said carriage in contact with said rim of the printing cylinder so that, if said cylinder is being rotated said pawl engages with said notch after one revolution of the cylinder so that said carriage 15 is lowered, an adjusting wheel for the counting mechanisms controlled from said carriage, a toothed wheel adapted to be engaged by said adjusting wheel, a counter toothed wheel, a locking pawl and a spring 20 pressing said locking pawl into the teeth of said counter toothed wheel.

10. In a rolling stamp of the type described in combination a main casing, a printing cylinder in said main casing, driving gears operated by the rotation of said printing cylinder, a supporting plate in said casing, a base plate for the counting mechanisms upon said supporting plate, a casing for the counting mechanisms, figure wheels in said casing, a 25 toothed wheel rigidly fixed in the extreme figure wheel, a toothed wheel with which said toothed wheel of the extreme figure wheel is in gear, an angle iron on the base plate, an axle in said angle iron, an angular toothed 30 wheel on said axle meshing with said toothed wheel of the extreme figure wheel, a locking disk above said angular toothed wheel, a locking scale on said locking disk, a carrier mounted on said axle of the angular toothed 35 wheel, a locking lever on said carrier adapted to engage with the notch of the locking scale by which the locking has to be effected, and a spring for keeping said locking lever in engagement with the locking notch.

40 11. In a rolling stamp of the type described in combination a main casing, a printing cylinder in said casing, stamp value rollers in said cylinder, means for operating said stamp value rollers if the printing cylinder is being 45 rotated, counting mechanisms in said main casing, means for operating said counting mechanisms if said printing roller is being rotated, a support in said main casing consisting of two lateral bearing rails and an intermediate piece, an angle piece on said intermediate piece, a lever located in said angle piece, a locking lever for the counting mechanisms, a locking lever adapted to be acted upon by said locking lever of the counting 50 mechanisms, an angle abutment of said locking lever of the counting mechanisms, a connecting lever with which said lever is connected, fork-shaped ends of said connecting lever embracing on the one hand said locking 55 lever and on the other hand said angular abut-

ment, a counter toothed wheel, a locking flange of said counter toothed wheel adapted to be stopped by said angular abutment, and a pull spring for returning said locking lever to the initial position as soon as the locking lever for the counting mechanisms is lifted out of the locking notch. 70

12. In a rolling stamp of the type described, an indicating device for the number of stamps or for the value of the stamps which may be printed before the apparatus is locked comprising in combination a counting mechanism, a mechanism for locking said counting mechanism, a carrier for the locking mechanism, a mark upon said carrier, and a ring 75 with figures in which said mark is situated so that it indicates on said ring the number of stamps or the stamp value which may be still printed. 80

13. In a rolling stamp of the type described the mechanism for giving an increased drive to the registers when such a multiplicity of faces is used that a single set of teeth on the feed wheels will not register a sufficient amount, comprising in combination a main 90 casing *a*, a printing cylinder *e* in said main casing, a hollow shaft *b* in said printing cylinder, stamp value rollers *91* in said printing cylinder, a drive *94* a bearing for said drive, an extension *33* of said bearing, a curved ring 95 *111* arranged in said extension, a shifter *115*, a reversing curve *116*, on said shifter, an adjusting lever *124* on said hollow shaft, a handle *124'* of said adjusting lever *124*, a hand *124''* of said handle, an adjusting scale *126* 100 on the top plate of said main casing *a* having value notches *124*, a ring-shaped bearing *115'* of said shifter, a shifting lever *106* bearing on said ring-shaped bearing *115'* adapted to be raised and lowered according to whether said hand *124''* is raised from one value notch 105 *127* to the other or engages with a notch, large feed wheels *112*, small feed wheels *111*, guide bushes *113* for said feed wheels, a shifting fork *106* on said shifting lever engaging with 110 said guide bushes *113*, driving wheels *110* for said stamp value rollers *91* adapted to be brought in gear either with said large or small feed wheels (*112*, *111*) and an adjuster in gear with said drives of said stamp value 115 rollers *91* for adjusting said rollers for the different values.

In testimony whereof I affix my signature.
HELENE KOMUSIN, née LIEDTKE.
